ATTORNEY

UNITED STATES PATENT OFFICE

FRANK FISHER, OF NEW YORK, N. Y.

CHRISTMAS-TREE-ORNAMENT FASTENER

Application filed March 23, 1929. Serial No. 349,302.

This invention relates generally to fasteners and has more particular reference to Christmas tree ornaments and light attachment means.

5 The invention has for an object the provision of a device of the class mentioned which is of simple durable construction, desirable in use and efficient in action, and which can be manufactured and sold at a reasonable 10 cost.

One of the objects of the invention is the provision of a device which is adapted to be conveniently secured upon a branch of a Christmas tree and which may be employed 15 to support and suitably position several ornaments or lights. Another object of the invention is the provision of adjustable means which may be manipulated for suitably disposing the ornaments or lights in desired 20 positions.

For further comprehension of the invention, and of the objects and advantages thereof, reference will be had to the following description and accompanying drawings, and 25 to the appended claims in which the various novel features of the invention are more particularly set forth.

In the accompanying drawing forming a material part of this disclosure:—

30 Fig. 1 is an elevational view of a device constructed according to this invention.

Fig. 2 is an edge view thereof.

Fig. 3 is a view similar to Fig. 1 but disclosing a modified form.

35 Fig. 4 is an edge view of Fig. 3.

Fig. 5 is an elevational view of the device constructed according to modified form, a portion thereof being shown in section.

40 Fig. 6 is a horizontal sectional view taken on the line 6—6 of Fig. 5.

Fig. 7 is a view similar to Fig. 5 but disclosing a further modified form.

The reference numeral 10 indicates generally a circular top ring of a fastening device 45 formed of one piece of resilient wire, this ring being open at the bottom as indicated by reference numeral 11 and wire arms 12 connecting with the ring at its opened portion.

These wire arms are curved outwardly as 50 indicated by numerals 13 forming a belly

portion and one of the arms terminate in an inclined end 14 providing an entrance 15 to the said belly portion. The other arm terminates in a loop 16 formed at right angles to the plane of the ring 10. The belly portion may be engaged upon a branch of a 55 Christmas tree and a Christmas light or ornament may be supported within the ring, the hook 16 may be used to support a light or any other Christmas ornament. 60

In the modified form of the device illustrated in Figs. 3 and 4, a fastening means has been shown composed of two pieces of wire indicated by numerals 17 and 18, respectively. These wires are twisted together at 65 their central portions as at 19, the top portions of the wires being curved to form gripping arms and a gripping opening 20, while the portion immediately below the twisted portion 19 is bulged as at 21 to form a belly 70 portion, one of the wires continuing and is curved around forming a hook 22. The hook 22 is disposed in the same plane as the plane of the gripping arms 20. The gripping arms 20 may be engaged upon a branch of a Christmas tree or may support a Christmas light or ornament and the belly portion and hook portion 22 may also support lights or ornaments. 75

In the modified form of the device illustrated in Figs. 5 and 6, a fastening means has been shown provided with a central twisted portion 19' formed of a top and bottom section, the top section being secured upon a top disc 23 and the bottom section on a bottom disc 24. The adjacent faces of these discs have interengaged teeth 25. A spring clip 26 is arranged for holding the discs together with their teeth interengaged. The spring clip 26 consists of radial arms 27 formed with an aperture 28 at their junctions thru which the twisted section 19' passes and each arm has an inturned bottom end 29 engaging against the bottom surface of the bottom disc 24. For changing the planes in which the hook 22 and the arms 17, 18 are arranged it is merely necessary to slightly pull the discs 23 and 24 apart and rotate them to any desired amount and finally release the discs which are 95 100

immediately reengaged by the said spring clips.

In the modified form of the device illustrated in Fig. 7, the fastening device is formed with a top pair of curved gripping arms 17, 18 connected with a twisted section 19' which is secured upon a top disc 23. This top disc coacts with a bottom disc 24 held in interengaged positions by a spring clip 26, said discs having interengaged teeth 25.

10 A small belly portion hook 21 is secured upon the bottom side of the lower disc 24 and supports a third disc 23' having teeth 25' interengaged with complimentary teeth on a fourth disc 24'. A spring clip 26' resiliently holds these discs together. A hook 22 is arranged upon the bottom side of the disc 24'. The planes of the arms 17, 18 and the belly portion 21 may be adjusted by drawing the discs 23 and 24 slightly apart against the action of the spring clip 26 and performing the necessary circular adjustments. In a similar manner the plane of the hook 22 may be changed relative to the plane of members 21 and 17, 18 by drawing the discs 23', 24' apart and rotate these discs relatively to any desired amount. The spring clip 26' will urge the discs together upon a releasing of the same.

30 While I have shown and described the preferred embodiment of my invention, it is to be understood that I do not limit myself to the precise construction herein disclosed and the right is reserved to all changes and 35 modifications coming within the scope of the invention as defined in the appended claims.

Having thus described my invention, what I claim as new, and desire to secure by United States Letters Patent is:—

40 1. In a fastening device of the class described, a hook comprising resilient wire adapted to be disposed over a branch of a Christmas tree, a disc attached to one extremity of said hook, a second disc disposed adjacent said first mentioned disc in superimposed relation thereto, and arranged for rotation relative to the first disc, resilient means acting between both discs for holding the discs in engagement with each other and 45 constituting the arrangement of holding the disc for relative rotations, a second hook member comprising resilient wire material attached to said second mentioned disc adapted to support a Christmas tree light 50 socket, and interengaging teeth on the adjacent surfaces of said discs for retaining the same in an adjusted position, said discs being adapted to be separated for disengaging the teeth thereof.

60 2. In a fastening device of the class described, a hook comprising resilient wire adapted to be disposed over a branch of a Christmas tree, a disc attached to one extremity of said hook, a second disc disposed 65 adjacent said first mentioned disc in super-

imposed relation thereto, a spring clip mounted on said first mentioned disc and engaged with said second mentioned disc for rotatively securing said discs in superimposed relation and urging the discs together, a hook member on said second disc and adapted to support a Christmas tree light socket, and said discs being arranged for retaining adjusted positions.

3. In a fastening device of the class described, a hook comprising resilient wire adapted to be disposed over a branch of a Christmas tree, a disc attached to one extremity of said hook, a second disc disposed adjacent said first mentioned disc in superimposed relation thereto and for urging the discs together, means for rotatively securing said discs in superimposed relation, a second hook member comprising resilient wire material attached to said second mentioned disc adapted to support a Christmas tree light socket, and interengaging teeth on the adjacent surfaces of said discs for retaining the same in an adjusted position, said discs being adapted to be separated against the action of said means for disengaging the teeth thereof.

In testimony whereof I have affixed my signature.
